UNITED STATES PATENT OFFICE.

ALLEN J. BECKER, OF ESSEX FELLS, NEW JERSEY.

CARBOY CARRIER.

Application filed January 10, 1921. Serial No. 436,190.

To all whom it may concern:

Be it known that I, ALLEN J. BECKER, a citizen of the United States, and a resident of Essex Fells, in the county of Essex and State of New Jersey, have invented a new and Improved Carboy Carrier, of which the following is a full, clear, and exact description.

This invention relates to improvements 10 in carboy carriers, an object of the invention being to provide a device with which carboys may be handled without danger to those engaged in the handling.

A great many accidents have been caused 15 in chemical plants because no safe and efficient means has heretofore been provided for the manual handling of large carboys of acid, the crude carriers now employed often causing the dropping and breaking of 20 the carboys and resultant damage from the burning acid.

It is an object therefore of this invention to provide a carboy carrier which will positively grip the carboy and obviate the danger of accidents.

A further object is to provide a device of 30 the character stated which will be simple and practical in construction, strong, durable, and efficient in use, and comparatively inexpensive to manufacture.

With these and other objects in view, the invention consists in certain novel features of construction, and combinations and arrangements of parts as will be more fully 35 hereinafter described and pointed out in the claims.

In the accompanying drawings:

Figure 1 is a broken top plan view of my improved device the dotted lines indicating 40 the position of a carboy within the carrier.

Figure 2 is an edge view of Figure 1.

Figure 3 is a view in transverse section on the line 3—3 of Figure 1.

Referring in detail to the drawings, 1, 1 45 represent a pair of parallel longitudinal side bars, preferably of rectangular cross section as indicated in Figure 3. The two bars 1 are connected by a pair of adjustable cross pieces 2. Each cross piece 2 includes 50 at each end an arm 3 rigidly connected to one of the bars 1 and projecting inwardly therefrom. Links 4 of equal length are each pivotally connected at one end to one of the arms 3, and at their other ends to each 55 other.

The cross pieces 2 are preferably a suffi-

cient distance apart to conveniently accommodate two carboys indicated in dotted lines at 5 between them. It will be readily seen that the two cross pieces by virtue of 60 the links 4, are adjustable as to length. It is absolutely essential for the safe handling of carboys that the two bars 1 be locked against spreading movement under the lugs or flanges indicated in dotted lines at 6. 65 Improved means are provided therefore for locking the cross pieces against movement to prevent accidental spreading of the bars 1.

On each one of the cross pieces 2 ratchet teeth 7 are secured to the upper face of one 70 of the arms 3. A thin spring steel strip 8 has one end secured to the other arm 3, and at its free end is made integral with a dog 9 engageable with the ratchet 7.

A headed bolt 10 which serves as a pivotal connecting member between the ratchet carrying arm 3 and the adjacent link 4 is movable through a longitudinal slot 11 in the strip 8 and serves to maintain the dog 9 in constant engagement with the ratchet 7. 80

By virtue of the construction above described it will be seen that the bars 1 may be readily advanced towards each other until they engage the sides of the carboys 5 under 85 the lugs or flanges 6, and that the ratchet and dog will prevent accidental spreading of the bars 1.

In order to permit spreading of the bars to release the carboys, a handle member 12 is 90 provided on the end of each strip 8 so that the dogs may be manually lifted out of engagement with the ratchet teeth. After the carrier has been locked in place under the lugs 6, the ends of the bars 1 are used as handles to lift and transport the carboys.

Various slight changes and alterations might be made in the general form and arrangement of the parts described without departing from the invention, and hence I 100 do not limit myself to the precise details set forth but consider myself at liberty to make such changes and alterations as fairly fall within the spirit and scope of the appended claims.

What I claim is:

1. In a carboy carrier, a pair of longitudinal bars, cross pieces connecting said bars, each of said cross pieces comprising inwardly projecting arms rigidly connected at 110 one end to the longitudinal bars, links, each pivotally connected at one end to one of the

arms, and at their other end to each other, ratchet teeth carried by one arm, and a spring held dog carried by the other arm and engageable with the ratchet teeth.

5 2. In a carboy carrier, a pair of longitudinal bars, cross pieces connecting said bars, each of said cross pieces comprising inwardly projecting arms rigidly connected at one end to the longitudinal bars, links, 10 each pivotally connected at one end to one of the arms, and at their other end to each other, ratchet teeth carried by one arm, a strip of spring metal fixed to the arm, a dog carried by the free end of the strip, and en-

15 gageable with the ratchet teeth.

3. In a carboy carrier, a pair of longitudinal bars, cross pieces connecting said bars, each of said cross pieces comprising inwardly projecting arms rigidly connected at 20 one end to the longitudinal bars, links, each pivotally connected at one end to one of the arms, and at their other end to each other, ratchet teeth carried by one arm, a strip of spring metal fixed to the arm, a dog carried by the free end of the strip and engageable 25 with the ratchet teeth, a headed bolt pivotally connecting the ratchet carrying arm

and one of the links, said strip having a longitudinal slot therein receiving the bolt, and a handle member on the free end of the strip 30 facilitating manual lifting of the dog out of engagement with the ratchet teeth.

4. In a carboy carrier, a pair of parallel handle bars, a pair of cross pieces connecting the bars, each cross piece including inwardly presented arms rigidly connected to the bars, ratchet teeth carried by one pair of arms, spring steel strips carried by the other arms, and dogs integral with the strips engageable with the ratchet teeth to hold said 40 bars against relative separation.

5. In a carboy carrier, a pair of parallel handle bars, a pair of cross pieces connecting the bars, each cross piece including inwardly presented arms rigidly connected to the bars, ratchet teeth carried by one pair of arms, spring steel strips carried by the other arms, and dogs integral with the strips engageable with the ratchet teeth to hold said bars against relative separation, said strips 45 terminating in integral handle members adapted to facilitate the manual disengagement of the dogs from the ratchet teeth.

ALLEN J. BECKER.
